UNITED STATES PATENT OFFICE

2,589,549

TWO TEMPERATURE REFRIGERATOR

George K. Iwashita, Nutley, N. J., assignor to Admiral Corporation, Chicago, Ill., a corporation of Delaware.

Original application July 14, 1943, Serial No. 494,629. Divided and this application June 16, 1950, Serial No. 168,596

7 Claims. (Cl. 62—117.3)

1

This invention relates to refrigerators and particularly to refrigerators of the type having two food storage compartments to be maintained at different temperatures. This application is a division of the copending application of George K. Iwashita, Serial No. 494,629, filed July 14, 1943 and issued on June 20, 1950, into Patent No. 2,511,851.

A primary object of this invention is to provide an improved two temperature, two compartment refrigerator which has advantages of construction and operation not possessed by prior art refrigerators.

Another object is to provide an improved two temperature, two compartment refrigerator of the type having primary and secondary refrigerant circulating circuits.

Another object is to provide an improved two temperature, two compartment refrigerator having a primary circuit provided with a single evaporator and having a secondary circuit arranged so as to be cooled by the primary evaporator and in turn cooling the second compartment.

Another object is to provide an improved two temperature, two compartment refrigerator having a primary refrigerant circulating system with a single evaporator which simultaneously refrigerates one of the compartments and the secondary condenser.

Another object is to provide a two compartment, two temperature refrigerator wherein the cooler of the two compartments also effects partial cooling of the other compartment.

Other objects and advantages will become apparent from the following description taken in conjunction with the accompanying drawing wherein:

Fig. 1 is a longitudinal medial cross-sectional view of a refrigerator embodying the present invention; and

Fig. 2 is a fragmentary medial cross-sectional view taken on the same plane as Fig. 1 but showing the arrangement of the primary evaporator and secondary condenser on the "frost chest" in greater detail.

The refrigerator indicated generally by the reference character 10 includes a front frame 12 to which are secured a main outer shell 14 and a pair of compartment defining liners 16 and 18, the liner 16 defining the "frost chest" 20 and the liner 18 defining the main food storage compartment 22. The refrigerator cabinet also includes a machinery compartment 24 which is closed at its upper side by panel 26 secured to the frame 12 and to the outer shell 14. The frame of the

2

refrigerator also includes a base frame 28 which supports the operating mechanism as will be described in greater detail hereinafter. The rear of the cabinet is closed by a panel 30 having an opening 31 which is closed by a removable panel 32 secured to the panel 30 by sheet metal screws 34. The space surrounding the liners 16 and 18 and enclosed by the shell 14, panels 26, 30 and 32 is filled with a suitable thermal insulating material 36. This insulating material may be of many different types including rock wool, balsa wool or the like. The access openings to the compartments 20 and 22 are closed by a single door 33 of any suitable construction which is provided with a deformable gasket 40 sealing against the front of the refrigerator cabinet. The door is preferably thermally insulated to prevent the escape of heat therewith.

The liner 18 is rigidly secured to the frame 12 and is permanently mounted in the cabinet. The liner 16 forming the frost chest 20 is removably held in position against the frame 12 by means of a pair of tensioned straps 42 secured at their forward ends to the frame 12; their rear ends are secured together at the back of the frost chest by a connector 44 which may be disconnected so as to provide for removal of the liner 16. Adjacent its rear, the frost chest liner 16 is additionally supported by a thermally nonconductive block 46 which is mounted on the outside of the ceiling of the liner 18. The space 47 forwardly of the block and between the liners 16 and 18 is not filled with thermal insulation and, therefore, there is a heat transfer by convection between the frost chest 20 and the compartment 22 through this space.

The compartments 20 and 22 are cooled by a primary refrigerating system 48 and a secondary refrigerating system 50. The primary system includes a refrigerant liquefier comprising a compressor 52 and a condenser 54 connected thereto. The outlet side of the condenser 54 is connected by a capillary tube 56 to the inlet of primary evaporator coil 58 which is secured to the outside of the liner 16 in heat exchange relation by metallic Permagum 60 which is a material possessing high thermal conductivity and may be a soft nonoxidizing material impregnated with aluminum flakes, graphite and the like. The evaporator coil 58 is therefore permanently secured to the outer surface of the liner 16 and when the primary system is removed from the refrigerator cabinet the liner 16 must also be removed. The outlet from the evaporator 58 leads to an accumulator 61 which is connected by a suction tube 59 to the compressor 52.

The secondary system 50 includes a condenser coil 62 connected to an evaporator coil 64 which is secured to the outer surface of the liner 18 in good heat exchange relation. The condenser coil is removably mounted on the side of the liner 16 by means of a bracket 66. The secondary condenser 62 is therefore in heat exchange relation with the walls of the liner 16 and through them with the evaporator 58 of the primary system. The primary evaporator thus directly refrigerates the frost chest 20 and simultaneously extracts heat from the refrigerant in the secondary system in order that the secondary system may withdraw heat from the larger storage compartment 22. The secondary condenser 62 is above the secondary evaporator 64 and the tubing forming this system is so arranged that the flow of refrigerant therethrough will be in one direction.

In order that the cooling of the compartment 22 may be improved, the space between the lower wall of the liner 16 and the upper wall of the liner 18 is left uninsulated, as previously mentioned, allowing heat transfer from the lower liner to the upper liner by convection.

The primary refrigerating system is very readily removed from the cabinet. First the small panel 32 is removed, and then that part of the insulation indicated by the reference character 68 may be removed without disturbing the rest of the insulation 36. This exposes the back of the liner 16, and the fastening 44 is disconnected. The liner 16 and the attached evaporator coil 58 is slid rearwardly after the secondary condenser coil 62 has been slipped from beneath the clamp 66 and moved to one side. Since the tubing is flexible, this movement of the condenser tubing 62 to one side is very easily carried out. The removal of the primary system from the cabinet is completed by removing the compressor 52 and condenser 54 from the machinery compartment 24. The primary system can, therefore, be hermetically sealed and, if necessary, returned to the factory for repairs. The primary refrigerant circulating system is replaced in the cabinet by carrying out the foregoing steps in the reverse order.

It will be obvious to those skilled in the art that numerous modifications and changes may be made in this refrigerator without departing from the fundamental principles of the invention, which is to be limited only by the scope of the appended claims.

What is claimed as new and desired to be secured by United States Letters Patent is:

1. A refrigerator comprising a liner which forms a low temperature compartment, a second liner spaced from the first which forms a higher temperature compartment, means for insulating both liners on all sides except the space between them, a secondary refrigerating system having a condenser portion in direct heat exchange relation with said low temperature compartment liner and an evaporator portion in direct heat exchange relation with said high temperature compartment liner, and a primary evaporator maintained in heat transfer relation with said low temperature compartment liner whereby it cools both the low temperature compartment and the secondary refrigerant.

2. A refrigerator comprising a liner which forms a low temperature compartment, a second liner spaced from the first which forms a higher temperature compartment, means for insulating both liners on all sides except the space between

them, a secondary refrigerating system having a condenser portion in direct heat exchange relation with said low temperature compartment liner and an evaporator portion arranged to cool said higher temperature compartment, and a primary evaporator maintained in heat transfer relation with said low temperature compartment liner whereby it cools both the low temperature compartment and the secondary refrigerant, the cooling of the higher temperature compartment being accomplished both by the secondary refrigerant and by convection in the uninsulated space between the liners.

3. A refrigerator comprising a liner which forms an upper low temperature compartment, a second liner spaced downwardly from the first which forms a lower high temperature compartment, means for insulating both liners on all sides except the space between them, a secondary refrigerating system having a condenser portion in heat exchange relation with said low temperature compartment liner and an evaporator portion in heat exchange relation with said high temperature compartment liner, and a primary evaporator maintained in heat transfer relation with said low temperature compartment liner whereby it cools both the low temperature compartment and the secondary refrigerant, the cooling of the higher temperature compartment being accomplished both by the secondary refrigerant and by convection in the uninsulated space between the liners.

4. A refrigerator comprising a liner which forms a low temperature compartment, a second liner spaced from the first and which forms a high temperature compartment, a secondary refrigerating system having a secondary condenser portion and having a heat absorbing portion in heat exchange relation with said high temperature compartment liner, and a primary refrigerating system having an evaporator coil in heat absorbing relation with both said low temperature compartment liner and said condenser portion of said secondary refrigerating system, said condenser portion of said secondary refrigerating system being in direct heat exchange contact with said low temperature compartment liner.

5. A refrigerator comprising a liner which forms a low temperature compartment, a second liner spaced from the first which forms a high temperature compartment, a secondary refrigerating system having a secondary condenser portion and having a heat absorbing portion in heat exchange relation with said high temperature compartment liner, and a primary refrigerating system removable from the refrigerator having an evaporator coil in heat absorbing relation with both said low temperature compartment liner and said condenser portion of said secondary refrigerating system, said condenser portion of said secondary refrigerating system being removably held in heat exchange contact with said low temperature compartment liner.

6. A refrigerator comprising a removable liner which forms a low temperature compartment, a second liner spaced from the first which forms a high temperature compartment, a secondary refrigerating system having a condenser portion and having a heat absorbing portion in heat exchange relation with the high temperature compartment liner, and a primary refrigerating system having an evaporator coil secured to and in heat absorbing relation with said low temperature compartment liner, and means removably

securing said condenser portion of said secondary refrigerating system in heat exchange contact with said low temperature compartment liner whereby said primary evaporator coil refrigerates both said low temperature compartment and said secondary condenser.

7. A refrigerator comprising a removable liner which forms a low temperature compartment, a second liner spaced from the first which forms a high temperature compartment, thermal insulation surrounding said liners on all sides except the space between them, a secondary refrigerating system having a condenser portion and having a heat absorbing portion in heat exchange relation with the high temperature compartment liner, and a primary refrigerating system having an evaporator coil secured to and in heat absorbing relation with said low temperature compartment liner; and means removably securing said condenser portion of said secondary refrigerating system in heat exchange contact with said low temperature compartment liner whereby said primary evaporator coil refrigerates both said low temperature compartment and said secondary condenser and the cooling of said high tempera- 25

ture compartment is accomplished both by said secondary heat absorbing portion and by convection in the uninsulated space between said liners.
